230,283

FIGURINE

Jimmy J. Johnson, Rte. 3, Box 533,
Wichita Falls, Tex. 76308

Filed May 24, 1972, Ser. No. 256,637

Term of patent 14 years

Int. Cl. D11—02

U.S. Cl. D29—23 A

FIG. 1 is a perspective view of a figurine showing my new design; and

FIG. 2 is a perspective view from the opposite direction.

The bottom of the base is substantially plain.

I claim:

The ornamental design for a figurine, as shown and described.

References Cited

Gift & Decorative Accessories, August 1965, p. 139—
Animal figurine of bolts top right center.

Yield House catalog, © 1966, p. 2—Don Quixote
figurine lower center.

Gifts & Decorative Accessories, September 1968, p.
74—Nuts 'n bolts figures at right bottom.

Gift & Decorative Accessories, February 1971, p.
112—Nuts & bolts boxers at lower center.

JOEL STEARMAN, Primary Examiner

L. S. ZARFAS, Assistant Examiner